UNITED STATES PATENT OFFICE.

CALVIN WOODWARD AND GEORGE M. WOODWARD, OF NEW YORK, N. Y.

IMPROVEMENT IN STEAM-PUMPS.

Specification forming part of Letters Patent No. 35,966, dated July 22, 1862.

To all whom it may concern:

Be it known that we, CALVIN WOODWARD and GEORGE M. WOODWARD, both of the city, county, and State of New York, have invented a new and useful Improvement in Steam-Pumps; and we do hereby declare that the following is a full, clear, and exact description of the same, reference being had to the accompanying drawings, forming part of this specification, in which—

Figure 1 is a side view of a steam-pump with our improvement. Fig. 2 is a transverse vertical section of the same. Fig. 3 is a central longitudinal section of the same.

Similar letters of reference indicate corresponding parts in the several figures.

This invention consists in combining a crank and fly-wheel with a direct-connection steam-pump by means of a vibrating link and sliding box arranged and operating substantially as hereinafter described.

A is the bed-plate having the steam-cylinder B and pump-cylinder C arranged horizontally upon it in line with each other.

D is the piston-rod which constitutes the direct connection between the steam-piston B' and the pump-piston C', having secured to it midway between the pistons a cross-head, E.

F is the shaft of the crank M and fly-wheel N, arranged in suitable bearings, a a, upon the bed-plate transversely to the piston-rod, and midway between the two cylinders, the crank-wrist b being opposite the piston-rod and the fly-wheel outside of the bed-plate.

G is the vibrating link, having a longitudinal slot, c, for the reception of the sliding box d, which is fitted to the crank-wrist, and having in its lower part a slot, e, which is fitted to slide on a square, f, formed upon a rock-shaft, H, which is arranged parallel with and some distance directly below the crank-shaft in bearings in two rigid hangers, g g, which are secured to opposite sides of the bed-plate. The upper end of this link is forked, as shown in Fig. 2, and in opposite sides of the fork are provided or secured boxes h h for the reception of the two journals j j of the cross-head on opposite sides of the piston-rod. On one end of the crank-shaft is the eccentric wrist I, which gives motion to a second vibrating link, J, by which the induction and eduction valve L of the steam-cylinder is operated, the lower end of

the said link being arranged to oscillate upon the rock-shaft H, and the upper end being connected with the valve-stem i.

Steam admitted at one end of the cylinder B drives the piston B' toward the other end, and the rod D moves the piston C' and link G in the corresponding direction, and the link produces half a revolution of the crank M, shaft F, and eccentric wrist I, and the said wrist brings the valve to a position to admit steam to the opposite end of the cylinder, when the motion of the piston B', rod D, piston C', and link G is reversed, and the revolution of the crank is completed, causing the wrist I to bring the valve to a position to admit steam again to the first-mentioned side of the piston; and in this way the operation is repeated, the link G having, besides its vibrating motion, a slight upward and downward movement, provided for by the slot e, equal to the versed sine of the arc that would be described by the centers of the boxes h h if the center of vibration were fixed, and the box d of the crank-wrist having a sliding movement upward and downward in the slot c c.

The application of a crank and fly-wheel, in combination with the direct connection of the pistons, renders the operation of the valve more certain than that produced by a tappet motion or any other valve motion actuated without a fly-wheel, and the connection of the crank-shaft with the piston-rod, by means of the vibrating link and sliding box, permits its arrangement between the cylinders where it occupies no room in a direction lengthwise of the cylinders, but, on the contrary, permits the cylinders to be brought a little closer together than when a tappet motion is used to work the valve.

What we claim as our invention, and desire to secure by Letters Patent, is—

Combining a crank and fly-wheel with a direct-connection steam-pump by means of a vibrating link, G, and sliding box d, arranged and applied in connection with the piston-rod and between the steam and pump cylinders, substantially as herein specified.

CALVIN WOODWARD.

GEORGE M. WOODWARD.
